INVENTOR:
18 RAYMOND HUTCHINSON,
BY *Gales P. Moore*
HIS ATTORNEY.

UNITED STATES PATENT OFFICE

RAYMOND HUTCHINSON, OF BRISTOL, CONNECTICUT, ASSIGNOR TO THE NEW DEPARTURE MANUFACTURING COMPANY, OF BRISTOL, CONNECTICUT, A CORPORATION OF CONNECTICUT

HEATING APPARATUS

Application filed October 9, 1928. Serial No. 311,369.

This invention relates to heating apparatus and comprises all the features of novelty herein disclosed. An object of the invention is to provide improved apparatus for heating articles and more especially one in which the heating chamber is well insulated and wherein the articles can be conveniently introduced and removed at selected stations. To these ends and to improve generally and in detail upon devices of this character, the invention further consists in the various matters herein-after described and claimed.

In its broader aspects, the invention is not necessarily limited to the specific construction selected for illustrative purposes in the accompanying drawings in which

Fig. 1 is a plan view.

Fig. 2 is a side elevation partly in section and

Fig. 3 is a diagram.

The base comprises a casing composed of a lower section 10 and an upper section 12 bolted together and supporting a vertical shaft 14 for rotation on ball bearings 16 and 18 in the casing. The shaft is driven at slow speed by a motor (not shown) connected to a worm 20 driving a worm wheel 22 keyed to the shaft. To the upper end of the shaft is keyed a spider 24 having vertical webs 26 bolted to a series of radial arms 28 in the form of angle irons to the horizontal legs of which are secured two flat superimposed rings, one ring 30 being of metal and the other ring 32 being of asbestos paper or the like to insulate articles carried on the ring 30 from heating apparatus below it. Ring 30 forms a rotary work support or carrier.

The hub 34 of a wheel or spider 36 is keyed to the shaft 14 and has a supporting ledge 38 for rings 40 and 42 of heat insulating material which insulate the wheel or spider from a heated shelf or table 44 which is secured to the wheel by bolts 46. The shelf or table forms a rotary work support or carrier. The rings 40 and 42 and the shelf or table are conveniently formed in segmental sections.

The shelf or table is enclosed within an insulated heating chamber 48 having en-

trance openings to insert the work. Supporting channel irons 50 radiate from the upper casing section 12 to which they are secured by bolts 52. At the ends of the channel irons are secured upright angle irons 54 secured at the top to horizontal angle irons 56 attached to and radiating from a ring 58 surrounding the shaft 14. A bottom plate 60, in the form of a ring, is fastened to the channel irons 50 and stiffened by angle irons 62. The plate 60 supports a thick ring of asbestos cement or the like recessed to receive arcuate plates 66 carrying heating units 68 which are located in a space narrower than that between depending flanges of the table or shelf 44 and supply heat to it. Two rings 70 and 72 of angle iron, bolted to the plate 60, form a channel 73 receiving a depending flange 74 on the wheel or spider 36. The channel is preferably filled with sand or some loose refractory material to seal the inner periphery of the annular heating chamber 48 containing the heating units. A circular plate 76 is secured to the horizontal flanges of the angle irons 56 and carries a ring 78 of angle iron entering a channel 79 in the wheel or spider 36. This channel is likewise filled with sand or the like to seal the joint.

The outer periphery of the annular heating chamber is closed by a cylindrical wall or board 80 preferably made in arcuate sections and composed of asbestos or similar heat resisting and insulating material bolted to the angle irons 54. The wall 80 and an angle iron ring 82 support a removable ring-like cover, preferably of the same material as the wall 80 and also made in arcuate sections 84, 86, 88 and 90. The section 84 has a notch or recess 92 registering with a notch or recess 94 in wall 80 to facilitate inserting a piece of work onto the rotary shelf or table 44 which carries the work around in the heating chamber. The work can be removed at any selected one of a series of unloading stations, the extent of arcuate travel being determined by the size of work or the time necessary to heat it. The section 86 has two notches or recesses 96 and 98 at which the work can be removed and the section 88 has one such notch or recess 100. The notches all register with notches in

the cylindrical wall 80 and the angular spacing of the notches varies in order that the arc of travel and hence the time of heating can be selective. For instance, the work 5 may be inserted at any one of the notches and removed from the same notch or any of the others. Also work of different sizes can be loaded at different stations and removed as desired and any notches not in use can be 10 temporarily covered by a heat insulating plate as indicated at 102 covering the notch 98.

To facilitate unloading, a deflector may be placed at any selected unloading station. One such deflector is shown at the station 96 15 and comprises a curved angle iron 104 pivotally attached at 106 to the cover section 86 and having its vertical flange 108 depending into the path of the work-pieces on the table 44 to deflect or cam them outwardly near the 20 periphery where they can be slid out through one of the notches in the cylindrical wall 80. The deflector can be clamped in any selected angular position by a clamping bolt 110 entering a slot 112 in an arcuate supporting 25 angle iron 114 bolted on top of the plate 76 and cover section 86 and extending out into the notch 96.

The speed of the table may be adjusted to 30 vary the amount of heating but, as indicated diagrammatically in Fig. 3, it is preferred to arrange the heating units in a plurality of independent series or sectors with each series having a plurality of selective resistance wires. A switch 116, for instance, has a wire 35 118 leading to one resistance wire in one series or sector, a wire 120 leading to another resistance wire, and a single return wire 122. One resistance wire will produce a low heat, another a greater heat, and both together a 40 still greater heat. Another switch 124 is similarly connected to heating units in another series or sector, etc. so that the heat supplied to the various sectors can be widely varied if desired. The switches may be 45 placed by thermostats for automatic control.

The apparatus can be used for heating or cooking a variety of things though more especially designed for heating metal parts which need to be expanded for assembly with 50 unheated parts. For instance, in assembling the balls of a ball bearing between the inner race ring and the outer race ring, insertion of the balls into the races is facilitated by heating the outer race ring. Sometimes the 55 two race rings are matched in which case the operator places the outer race ring on the table 44 at one of the loading stations and places the inner race ring on the rotary ring 30 above it. Both articles then travel 60 at the same speed to the selected unloading station where they are taken off and assembled with the balls.

I claim:

1. In apparatus of the character described, 65 a casing, heating devices in the casing, a mov-

able carrier mounted in the casing to carry articles past the heating devices, a second movable carrier outside the casing and movable in unison with the first carrier, and heat insulating material between the carriers to 70 obstruct access of heat from the casing to articles outside the casing on the second carrier; substantially as described.

2. In apparatus of the character described, 75 a casing having heat insulating walls, heating devices in the casing, an annular carrier rotatable in the casing adjacent to the heating devices, a rotary wheel supporting the carrier, and heat insulating means interposed between the carrier and the wheel; substantially as described.

3. In apparatus of the character described, 85 a casing, heating devices in the casing, a movable carrier mounted in the casing to travel past the heating devices, the casing having an unloading station, a deflecting arm pivoted to the casing and arranged adjacent to the unloading station, and means for securing the arm in adjusted position; substantially as described.

4. In apparatus of the character described, 90 a casing, heating devices in the casing, a circular carrier mounted inside the casing and rotatable past the heating devices, and a second rotatable carrier of circular form mounted outside the casing and above the first carrier, said second carrier being rotatable in unison with the first carrier and comprising a supporting ring with a layer of heat insulating material between it and the casing; 95 substantially as described.

5. In apparatus of the character described, 100 a circular casing, heating devices in the casing, a circular carrier mounted inside the casing, a shaft for rotating the carrier and projecting through the top of the casing, the upper wall of the casing having loading openings, and a second circular carrier mounted on the upper end of the shaft and having a smaller diameter than the first carrier; 105 substantially as described.

6. In apparatus of the character described, 110 a casing, heating devices in the casing, a circular carrier mounted inside the casing, a shaft for rotating the carrier and projecting through the top of the casing, and a second carrier of circular form secured to the shaft outside the casing, said second carrier comprising an upper ring with a layer of heat insulating material between it and the casing; 115 substantially as described.

7. In apparatus of the character described, 120 a casing having heat insulating walls, an annular carrier rotatable in the casing, a rotary wheel supporting the carrier, heat insulating means interposed between the carrier and the wheel, the annular carrier having depending flanges at its inner and outer peripheries, and heating devices in the casing below the carrier and included within a space 125

narrower than that between said flanges; substantially as described.

8. In apparatus of the character described, a circular casing, heating devices in the casing, a circular carrier mounted inside the casing, means for rotating the carrier, the upper wall of the casing and the outer wall having registering notches forming loading and unloading stations at the periphery of the carrier, and said stations being spaced apart at various angular distances; substantially as described.

In testimony whereof I hereunto affix my signature.

RAYMOND HUTCHINSON.
